NUNZIO PAGANELLO, OF BROOKLYN, NEW YORK

FIGURETTE

Application filed January 21, 1931. Serial No. 510,094.

This invention relates to figurettes and has for an object to provide a joint between the trunk and support, whereby the figurette will be capable of being moved to assume many different positions of grotesque and amusing characterizations.

Another object is to provide a figurette having a support which includes the feet, the lower limbs, thighs and hips, which embodies a unitary structure, and between which hips the lower end of the trunk is yieldingly and movably connected.

Another object is to provide a joint between the trunk and support which will permit the trunk to be swung in a wide circle to assume various angles and be maintained in any one of the angles by frictional contact of the coacting surfaces.

Another object is to provide certain improvements in the form, construction and arrangement of the several parts whereby the above named and other objects may effectively be attained.

A practical embodiment of my invention is represented in the accompanying drawing, in which

Fig. 1 represents a side elevation of my figurette showing in dotted outline the trunk and adjacent parts in different positions;

Fig. 2 represents a front elevation of the same;

Fig. 3 represents a detail vertical section taken in the plane of the line III—III of Fig. 2 looking in the direction of the arrows; and

Fig. 4 represents a detail vertical section taken in the plane of the line IV—IV of Fig. 1 looking in the direction of the arrows.

The figurette comprises a support denoted by 1, a hollow trunk denoted by 2 movable on said support and having a head 3 and arms 4, 5 hinged to swing on the trunk.

The support 1 comprises feet 6, 7, legs 8, 9, thighs 10, 11, hips 12, 13, which thighs and hips are connected at 14 to form a unitary structure capable of supporting the trunk and its adjacent parts. The portion of the support between the hips 12, 13 is formed with a concave recess 15 which is arranged to receive the convexed lower end 16

of the hollow trunk 2. The trunk 2 is provided with inwardly projecting sockets 17, 18 for the reception of semi-spherical ends 19, 20 of the arms 4, 5, respectively. The convexed lower end 16 of the trunk is maintained in position in the concave recess 15 of the support 1 by means of a link 21 of metal or other suitable material which has one end secured in the connection 14, while the other end is extended upwardly and its outer end is formed into a hook 22. This link 21 extends upwardly from the center of the concave recess 15 through an enlarged hole 23 in the convexed end 16 of the trunk and toward the center thereof, so that the hook 22 will engage an elastic connection 24. The elastic connection 24 has one end fixed to an eye 25 in the semi-spherical end 19 of the arm 4, which eye extends inwardly through a hole 26 in the wall of the socket 17. The other end of the connection 24 is secured to an eye 27 extending inwardly from the semi-spherical end 20 of the arm 5 through a hole 28 in the wall of the socket 18.

In order that the figurette may assume a sitting posture, as shown in dotted outline in Fig. 3, the convexed lower end 16 of the trunk is cut away to form an elongated slot 29 which extends upwardly from the hole 23 to permit the movement of the link 21 therein. Thus it will be seen that the elastic connection 24 will be stretched a sufficient distance so as to be engaged by the hook 22 and thereby maintain a tension which serves to hold in frictional contact the semi-spherical ends 19, 20 in their sockets 17, 18 as well as the convexed end 16 of the trunk in its concave recess 15.

By this construction and arrangement, the trunk may be moved to various angular positions on the support and be maintained in such positions by the frictional contact of the coacting parts.

It is obvious that various changes may be resorted to in the form, construction and arrangement of the several parts without departing from the spirit and scope of my invention; and hence, I do not intend to be limited to the details herein shown and de-

scribed except as they may be included in the claim.

What I claim is:

In a figurette, a unitary support including feet, lower limbs, thighs and hips and provided with a concave recess extending over the upper surface thereof between the hips, a hollow trunk having its lower end convexed to oscillate in said concave recess, said convexed end of the trunk having an enlarged central opening and an elongated slot extending laterally and upwardly therefrom into the body of the trunk, a rigid link having one end fixed in the bottom of the concave recess of the support and arranged to extend upwardly therefrom through said opening or slot into the hollow trunk, said opening and elongated slot being disposed to accommodate the position of the link with respect to the support and trunk, and an elastic connection having its ends secured in the hollow trunk and disposed to engage the upper end of said link intermediate of said elastic connection for maintaining a uniform tension between the concave and convex surfaces of the support and trunk.

In testimony, that I claim the foregoing as my invention, I have signed my name this 20th day of January 1931.

NUNZIO PAGANELLO.
